UNITED STATES PATENT OFFICE.

OSCAR M. LEICH, OF CHICAGO, ILLINOIS, ASSIGNOR, BY MESNE ASSIGNMENTS, OF ONE-THIRD TO SAID LEICH, ONE-THIRD TO J. G. IHMSEN, AND ONE-THIRD TO MAX W. ZABEL, OF CHICAGO, ILLINOIS.

TELEPHONE SYSTEM.

No. 799,010.

Specification of Letters Patent.

Patented Sept. 5, 1905.

Application filed February 9, 1900. Serial No. 4,614.

To all whom it may concern:

Be it known that I, OSCAR M. LEICH, a citizen of the United States, residing at Chicago, in the county of Cook and State of Illinois, have invented a certain new and useful Improvement in Telephone Systems, of which the following is a full, clear, concise, and exact description, reference being had to the accompanying drawings, forming a part of this specification.

This invention relates to signaling systems in general, but more particularly to electric signaling apparatus for use in telephone-exchange systems, and especially to telephone-exchange systems of that type in which a plurality of subscribers' stations are connected with a single line, such systems being commonly known as "party-line systems." It is evident in a telephone system of this particular character that it is of advantage and that it is a feature which adds considerably to the efficiency and desirability of the system to have the apparatus so arranged that the operator at the central station may ring the bell of any subscriber's station on a line without ringing any of the other bells connected with the same line, thus avoiding the necessity of ringing all the bells each time it is desired to call up any particular subscriber on the line, and thereby dispensing with the necessity of employing a different number of rings for the different subscribers. In the improved signaling system and with the hereinafter-described arrangement of circuits and devices it is possible for the operator at the central station to selectively ring the subscribers' bells on any particular party-line—that is to say, the operator may ring any bell without ringing the others; and this very desirable and advantageous feature of selectively calling up any of the subscribers on a line is accomplished by means of the improved apparatus and in a very simple and efficient manner. For example, in a party-line telephone system embodying the principles of this invention each line may be common to four subscribers' stations—that is to say, four subscribers' telephone sets may be connected with each line in the usual and well-known manner, but with the exception that the equipment at each substation includes the improved signal-receiving apparatus.

In the particular embodiment of the inven-

tion hereinafter described there are two ordinary polarized bells, one of which is connected between one conductor of the line and earth and the other of which is connected between the remaining conductor and earth, and each ground connection includes an impedance element of such character that either bell will ring when a capacity charge is passed over the circuit. There are also in this arrangement two similar bells connected, respectively, between opposite sides of the line and earth, and in each of these last-mentioned ground connections there is a suitable impedance element, the impedance or reactive means in this case, however, being so adjusted or employed relatively to their allotted bells that the latter will not respond when a capacity charge is passed over the circuit. Thus the first two-mentioned bells respond readily to a capacity charge—that is to say, an alternating current which has been passed through a condenser and which may have thus become what is commonly known as "leading-current"—while the last two mentioned bells, owing to the difference in the adjustment or relative arrangement of the reactive means, do not respond to such capacity charges, but do respond to ordinary alternating currents. In this way with this arrangement one side of the line is connected with two bells, one responsive to capacity charges, the other non-responsive to such charges, and the same condition exists with respect to the other side of the line; and in the particular embodiment shown the apparatus at each substation, although it necessarily includes suitable reactive means for determining which of the different currents shall pass through its allotted bell or shall produce an effective flow of current through its allotted bell, is non-tuned in character and is responsive to vibratory currents of certain electrical character, but not to the vibratory currents of different character employed for ringing the other bells along the line. Obviously, therefore, it is possible to operate a party-line having a plurality of bells or other suitable signal-receiving devices, the same being responsive to selective signals conveyed over the circuit, and it will be understood that suitable means are provided, as hereinafter more fully described, at the calling or central station for sending the selective currents over the circuit,

and it will also be understood, of course, that this invention as applied to telephone systems is equally applicable to the common-battery or magneto systems.

5 As will be seen, the expression "capacity charge" has been used to denote currents which have passed through a condenser, the effect being to change the electrical character of the current which would otherwise be furnished directly from the source of current; but other means than reactance may, however, be employed to determine the character of the currents which are impressed on the line.

15 In the accompanying drawings, Figure 1 is a side elevation of signaling means, the inclosure being shown in section. Fig. 2 is a view on line 2 2 of Fig. 1. Fig. 3 is a diagrammatic view showing the connections of a signaling device which may be employed in connection with the system. Fig. 4 is a diagrammatic view of signaling means. Fig. 5 is a diagrammatic view of a signaling system embodying the principles of this invention.

25 As thus illustrated, and referring particularly to Fig. 5, there is shown a party-line-telephone circuit comprising the station sets 1, 2, 3, and 4 distributed throughout its length and included or adapted for inclusion with the conductors 5 and 6 of the circuit. As herein shown, the invention is applied to the common-battery system; but its application to other systems will be readily apparent, and there is also an independent telephone set 7, the said set being shown in operative association with the party-line circuit 5 6, the ordinary operator's set, ringing-key, drops, and clearing-out drop being indicated. With respect to stations 1 and 2, ordinary polarized bells 8 and 9 are employed, bell 8 being connected between conductor 5 and the earth 10 and bell 9 being connected between conductor 6 and the earth 10 through the agency of switch-hooks suitably connected to the circuit. The arrangement also includes an inductive reactance consisting, preferably, of the impedance-coils 11 11 in the circuits of the call-bells 8 and 9, and also, preferably, includes condensers 12 12 in the same circuit when the invention is applied to common-battery systems. The condensers 12 12 are so arranged that they will obstruct the passage of direct current—as, for instance, from the common battery at the exchange—but these condensers will not neutralize to any extent the inductive reactances 11 11. The reactances 11 11 are preferably of such high impedance that the currents which will pass therethrough, due to the ordinary telephone-generators, are not sufficient to ring the bell. The bell, however, is adapted to be operated when a current with a capacity charge such as would result when the current from the generator be passed through a condenser is sent over the line, the effect of 60 the reactances 11 11 being overcome by the

action of the condenser, thereby operating the bell. A detail of this bell-circuit diagrammatically is shown in Fig. 3, no condenser being shown, as would be the case in the ordinary ring-down system. The switch-hook is here omitted for the sake of clearness and call-bell 8 is adapted to operate when conductor 5 is suitably energized, while call-bell 9 is adapted to respond to a suitable energization of conductor 6. In order to operate an additional number of non-interfering signals upon the same line, there are also in this instance two of the improved calling devices 13 13 at stations 3 and 4, the same being shown in detail in Figs. 1 and 2. One of the 80 said calling devices is preferably connected between conductor 5 and the earth 10, while the remaining calling device is connected between conductor 6 and the earth through the agency, preferably, of switch-hooks. 85

In this improved signaling device there is preferably an alternating-current calling device consisting of electromagnets 14 14, operatively associated with an armature 15, pivotally secured between the same. The armature is adapted to operate the signal, preferably by means of a hammer 16 and bells 17, and the magnets are susceptible to alternating-current impulses passed therethrough, thereby operating the armature. In order to 95 lock the armature 15—that is, prevent the same from operating when current from a condenser is passed over the conductors 5 and 6—it is possible to employ auxiliary magnets 18, also energized from the same circuit, and to provide an extension 19 upon the armature 15, the said extension being preferably provided at its extremity with an armature 20, which is adapted to be influenced through the energization of the magnets 18. It will be 105 seen that in the present instance the magnets 18 are adapted to more easily influence the action of the armature 15, as the same acts thereon through the agency of a longer lever-arm, supplied in this instance by the extension 19. It is preferable to include a choke-coil 21 in series with the magnets 18, so as to materially increase the impedance of this circuit, and to include the magnets 14 14 in parallel with the magnets 18 and coil 21, this parallel circuit being included in series with the calling-circuit and preferably a condenser 12. When an ordinary alternating current is impressed upon the circuit including calling devices 13, the choke-coil 21 will effectively prevent the requisite energization of magnets 18 18 to operate the extension 19, and the calling device may be operated through the agency of the magnets 14 14, the impedance of which is not as great as the combined impedance of magnets 18 and coil 21. If a current from a condenser or any current having a capacity effect be impressed upon the calling-device circuit, the capacity effect overcomes in a measure the inductive reactance of 115 120 125 130

the coil 21, and the magnets 18 18 may be sufficiently energized to attract the armature 20, and thereby the extension 19, thus locking the armature 15 in place, the effect of magnets 18 being of greater influence thereon, due to the preferably longer lever-arm 19.

In order to convey ordinary alternating currents over the conductors 5 and 6 separately, as well as condenser-currents, it is practicable 10 to employ a generator 22, one of the terminals of which is suitably grounded, the remaining terminal 23 being adapted for connection with conductors 5 or 6 through the agency of switching means $s^1 s^2 s^3 s^4$, employed 15 for this purpose. Switching means s^3 is adapted to connect terminal 23 of the generator to conductor 5, thereby sending an alternating current over the said conductor, and switching means s^4 is adapted in a like manner 20 to connect terminal 23 of the generator to conductor 6. Switching means s' may be employed for connecting terminal 23 of the generator to conductor 5 in series with a condenser c' , and a capacity current is thus impressed 25 upon the said conductor, the capacity effect neutralizing all or a portion of the inductance in the circuit, as desired. Switching means s^2 in like manner includes the generator 22 in series with the conductor 6 and 30 a condenser c^2 , thus similarly energizing the said conductor, and any suitable switching means may be employed for effecting this result, the generator being also adapted, as shown, to energize other circuits of the 35 change.

In Fig. 4 there is shown an improved call-signal device or signal-receiving apparatus applied to an ordinary "ring-down" system, the condenser 12 being omitted, as will be 40 well understood, armature 15 being shown as locked by the magnet 18, thus preventing the operation thereof through the agency of the magnets 14 14, and the switch-hook is omitted in this instance for the sake of clearness, its 45 inclusion in the circuit being well understood.

The operation of the improved system will now be readily apparent. The call-signal devices at stations 1 and 3 are in this instance in circuit with conductor 5, call-signal devices 50 at the stations 2 and 4 being in circuit with conductor 6. If now switching means s' is operated at the exchange, generator 22 is included in series with conductor 5 and the condenser c' . A condenser-current is thus impressed 55 upon the calling-circuits connected to the said conductor 5—that is, the calling-circuits at stations 1 and 3. This current overcomes the inductive reactance of the choke-coil 11 at station 1 and operates the bell or 60 call-signal device 8. This current is also impressed upon the call-circuit at station 3, and the effect of the said current is to neutralize or partially neutralize the inductive effect of the choke-coil 21, thus sufficiently energizing 65 magnets 18 and locking the armature, there-

by preventing the operation thereof. In like manner switching means s^2 is employed when it is desired to operate the call-signal device 9 at the station 2, conductor 6 being in this instance energized and call-signal device 13 at 70 station 4 being prevented from operating, due to the effect of the magnets 18. When it is desired to operate the call-signal magnets at stations 3 and 4, switching means s^3 are employed. To call station 3, switching means s^3 is operated 75 to include the generator 22 in circuit with conductor 5, the ordinary generator-current being thus transmitted over the line. This current is impressed upon the calling-circuit at the said station, the greater portion thereof flowing through the magnets 14 14 and operating the bell or signal, magnet 18 being insufficiently energized to operate its armature 20, preferably due to the effect of the choke-coil 21. The current in this case is also impressed 80 upon the calling-circuit at station 1; but the signal 8 is prevented from operating, due to the action of the impedance-coil 11. In like manner the call-signal device at station 4 may be operated upon employment of the switching means s^4 . In the illustration shown, in 85 which condensers 12 12 are employed, so that no current from the common battery may leak through the call-signal devices, the capacity in these condensers is sometimes large 90 enough to require auxiliary inductance to neutralize the same, so that the calling devices may operate satisfactorily. Ordinarily a separate inductance is placed in the circuit with each one of these condensers, which produces more or less additional expense in the installation of systems of this class. To obviate this difficulty, it is desirable to provide 95 a single inductance-coil 24, which is adapted to overcome the capacity of the condensers 12 100 when the ringing-keys s^3 and s^4 are in action.

As illustrated, the invention is applied particularly to party-line telephones; but obviously it is not limited to such application nor to any particular number of stations. 105

It will be seen that the improved signal-receiving apparatus is in at least one case—that is to say, the apparatus of at least one substation—essentially non-tuned in character. In other words, alternating currents and reactive means are employed for selectively operating the different signals; but it will be seen that the reactive means associated with at least one subscriber's bell or other signal 115 is essentially of a non-tuned character.

The use of alternating currents or of vibrating currents of different character for selectively operating a plurality of signals through the medium of means including non-tuned reactive means located at one substation, at least, 120 is new. Furthermore, it will be seen that this invention, as previously stated, involves the use of non-tuned reactive signal-receiving apparatus at one subscriber's station at least and signal-transmitting apparatus at the central 125 130

station adapted for sending vibratory currents of different character; but the transmitting and receiving apparatus are adapted, by reason of the ability of the one to send currents which will produce different reactionary effects in the same reactive means and the other to develop different reactionary results at the different stations from a given current to conjointly increase and decrease the relative flow of current in the bells, whereby the bells at the different stations may, notwithstanding the absolutely non-tuned character of the signal-receiving apparatus of at least one substation, be selectively operated by vibratory currents of different character projected over the line. In other words, the desired result or selective action is obtained by the use of vibratory currents of different reactive character relatively to a given impedance in combination with reactive means in non-tuned signal-receiving apparatus of at least one substation, whereby the relative flow of current in the bells will vary as the current changes and the reaction varies. That the term "non-tuned" as applied to the improved signal-receiving apparatus accurately describes such apparatus is evidenced by the fact that none of the well-known principles of resonance, harmonics, &c., and no tuning, either electrical or mechanical, of any sort enters into or in any way characterizes the construction of the signal-receiving apparatus of at least one substation.

It is obvious that other suitable or desired translating devices may be substituted for the bells or signal-giving devices.

As illustrated it will be seen that the improved signaling system involves a plurality of signal-receiving means, the different signal-receiving means being each adapted, employed and designed independently of the operation or any signaling action of the other to perform its function of giving a signal to attract attention, it being possible to at will cause any one of the said signal-receiving means to give a signal to attract attention and without first causing the operation of another of said signal-receiving means. Furthermore and more specifically considered, it will be seen that the present invention contemplates a party-line telephone system in which a telephone set is allotted to each signal-receiving means, and in such case it is evident that the talking-circuits of the different telephone sets are in part coincident with each other and that each talking-circuit is in part coincident with a signaling-circuit.

With one of my improved non-tuned but reactively selective signal-receiving means of any suitable character or construction it will be seen that should the current change ever so gradually from one character to the other the reactive qualities are adapted to gradually change the supply of current to the said means—that is to say, should the current

change gradually in character the variation in the flow of current through the signal-receiving means will also be gradual—so that the apparatus for furnishing and switching and changing the currents at the central station may be of any suitable character.

As is well known, the laws or principles which underlie electrical tuning and electrical resonance are analogous to those which underlie acoustical tuning and acoustical resonance, the principles which govern electrical tuning being practically the same as those which govern mechanical tuning, and in the foregoing description and in the following claims it will be understood that wherever the term "non-tuned" is used I mean thereby that the circuit or the device or the apparatus is not tuned either electrically or mechanically and is not responsive merely to a certain frequency of vibration—that is to say, is not so adjusted as to make its natural period equal to the period of the impressed electromotive force. In other words, the process of adjusting the natural period of a conductor or of anything else so as to render it resonant is called "tuning," and for this reason, as stated, the term "non-tuned" in the foregoing description and in the following claims is used to designate a conductor or circuit, a mechanical device, or a piece of apparatus, which has no adjustment either mechanical or electrical with a view to so adjusting its natural period as to render it resonant or responsive only either directly or indirectly to electrical vibrations having an equal or similar period. Also in the following claims I desire to have each claim construed as broadly and liberally as the prior state of the art will permit—that is to say, as broadly and liberally as can be done in view of what the prior art actually and as a matter of fact discloses—and I desire that no limitations whatever be imposed upon said claims except in so far as may be found necessary or proper in view of what is actually disclosed by the prior art, and with this understanding.

What I claim as my invention is—

1. An electric signaling apparatus comprising an electromagnet for operating a signal, normally non-neutralized inductive means for preventing the operation of the said electromagnet upon neutralization of inductance in the said means, and means for at will causing said neutralization.

2. A party-line telephone system comprising a plurality of signal-receiving means, at least one of said means including an electromagnet for operating a signal, and normally non-neutralized inductive means for preventing the operation of the said electromagnet upon neutralization of inductance in the said means, said system also comprising means for at will causing said neutralization, and for furnishing current for operating said signal-receiving means; and a telephone set allotted

to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying current necessary for operating said telephone sets, said means being independent of and distinct from the means employed for furnishing the current necessary for operating the different signal-receiving means.

3. An electric signaling apparatus comprising a polarized electromagnet for operating a signal, normally non-neutralized inductive means for preventing the operation of the said electromagnet upon neutralization of inductance in the said means, and means for at will causing said neutralization.

4. A party-line telephone system comprising a plurality of signal-receiving means, at least one of said means including a polarized electromagnet for operating a signal, and normally non-neutralized inductive means for preventing the operation of the said electromagnet upon neutralization of inductance in the said inductive means, said system also comprising means for furnishing current for operating said signal-receiving means, and for at will causing said neutralization; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

5. An electric signaling apparatus comprising an electromagnet for operating a signal responsive to alternating currents, an auxiliary electromagnet for mechanically locking the armature of the aforesaid electromagnet, and controlling its operation, and reactive means associated with the said auxiliary electromagnet and governing the operation thereof.

6. A party-line telephone system comprising a plurality of signal-receiving means, at least one of said means including an electromagnet for operating a signal responsive to alternating currents, an auxiliary electromagnet for mechanically locking the armature of the aforesaid electromagnet, and controlling its operation, and reactive means associated with the said auxiliary electromagnet and governing the operation thereof, said system also comprising means for furnishing current for operating said signal-receiving means; and a

telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

7. An electric signaling apparatus comprising an electromagnet and an armature for operating a signal responsive to alternating currents, an auxiliary electromagnet for locking the armature in position, means for preventing the operation of the said electromagnet upon neutralization of inductance in the said auxiliary electromagnet, and means for causing said neutralization.

8. A party-line telephone system comprising a plurality of signal-receiving means, at least one of said means including an electromagnet, and an armature for operating a signal responsive to alternating currents, an auxiliary electromagnet for locking the armature in position, means for preventing the operation of the said electromagnet upon neutralization of inductance in the said auxiliary electromagnet, said system also comprising means for furnishing current for operating said signal-receiving means, and for causing said neutralization; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

9. An electric signaling apparatus comprising an electromagnet and an armature for operating a signal responsive to alternating currents, an auxiliary electromagnet for locking the armature in position, an impedance-coil included in circuit with the said auxiliary electromagnet, said auxiliary electromagnet being adapted to lock the armature upon neutralization of reactance in the said impedance-coil, and means for causing said neutralization.

10. A party-line telephone system comprising a plurality of signal-receiving means, at least one of said means including an electromagnet, and an armature for operating a signal responsive to alternating currents, an auxiliary electromagnet for locking the armature in position, an impedance-coil included in cir-

cuit with the said auxiliary electromagnet, said electromagnet being adapted to lock the armature upon neutralization of reactance in the said impedance-coil, said system also comprising means for furnishing current for operating said signal-receiving means, and for causing said neutralization; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

11. A signaling system comprising an electric circuit, a plurality of signal-receiving devices connected with the said circuit, a source of alternating current adapted to energize the said circuit, means for including the said source in the said circuit to operate one of the signal-receiving devices, and means for inserting capacity in circuit with the said source of alternating current and the said circuit, whereby another of the said signals may be operated.

12. A party-line telephone system comprising an electric circuit, a plurality of signal-receiving means connected with the said circuit, a source of alternating current adapted to energize the said circuit, means for including the said source in the said circuit to operate one of the signal-receiving means, and means for inserting capacity in circuit with the said source of alternating current and the said circuit, whereby another of the said signal-receiving means may be operated; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

13. A signaling system comprising a metallic electric circuit, a plurality of signal-receiving devices connected with one conductor of the said circuit and a return-circuit, a second plurality of signal-receiving devices connected between the remaining conductor of the circuit and the common return-circuit, a source of alternating current, means for including the said source of alternating current with one of the conductors of the circuit and the common

return-circuit, whereby one of the said signal-receiving devices may be operated, and means for inserting capacity in circuit with the said source of alternating current and the same conductor and the return-circuit for operating a second signal-receiving device connected with the said conductor.

14. A party-line telephone system comprising a metallic electric circuit, a plurality of signal-receiving means connected with one conductor of the said circuit and a return-circuit, a second plurality of signal-receiving means connected between the remaining conductor of the circuit and the common return-circuit, a source of alternating current, means for including the said source of alternating current with one of the conductors of the circuit and the common return-circuit, whereby one of the said signal-receiving means may be operated, and means for inserting capacity in circuit with the said source of alternating current and the same conductor and the return-circuit for operating a second signal-receiving means connected with the said conductor; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

15. A signaling system comprising an electric circuit, a plurality of polarized signals at different stations, an impedance-winding in circuit with one of the said signals, a source of alternating current adapted for inclusion with the said circuit at another station, and means for inserting capacity in circuit with the said source of alternating current and the said circuit, whereby inductance of the said impedance-winding is neutralized at will to operate the said signal.

16. A party-line telephone system comprising an electric circuit, a plurality of polarized signal-receiving means at different stations, an impedance-winding in circuit with one of the said signals, a source of alternating current adapted for inclusion with the said circuit at another station, and means for inserting capacity in circuit with the said source of alternating current and the said circuit, whereby inductance of the said impedance-winding is neutralized at will to operate the said signal; and a telephone set allotted to each signal-receiving means and designated by the signal given thereby, together with a talking-circuit for each telephone set, the talking-circuits of the different telephone sets being in part coincident with each other, and each said talking-

circuit being in part coincident with a signaling-circuit; and means for supplying the current necessary for operating said telephone sets, said means being independent of and distinct from the means employed for furnishing current necessary for operating the different signal-receiving means.

17. A signaling system comprising a metallic electric circuit, a plurality of signal-receiving devices connected with one conductor of the said circuit and a return-circuit, a second plurality of signal-receiving devices connected between the remaining conductor of the circuit and the common return-circuit, a condenser included in each of the circuits including a signal-receiving device, a source of alternating current, means for including inductance in circuit with the said source of alternating current and one of the conductors of the circuit and a common return-circuit, whereby one of the said signal-receiving devices may be operated, the said inductance serving to neutralize the capacity in circuit with the said receiving device, and means for at will inserting capacity in circuit with the said source of alternating current and the said conductor and the return-circuit for operating a second signal-receiving device included with the said conductor.

18. A party-line telephone system comprising a metallic electric circuit, a plurality of signal-receiving means connected with one conductor of the said circuit and a return-circuit, a second plurality of signal-receiving means connected with the remaining conductor of the circuit and the common return-circuit, a condenser included in each of the circuits including a signal-receiving means, a source of alternating current, means for including inductance in circuit with the said source of alternating current and one of the conductors of the circuit and a common return-circuit, whereby one of the said signal-receiving means may be operated, the said inductance serving to neutralize the capacity in circuit with the said receiving means, and means for at will inserting capacity in circuit with the said source of alternating current and the said conductor and the return-circuit for operating a second signal-receiving means included with the said conductor; and a telephone set allotted to each signal-receiving means and designated by the signal given thereby, together with a talking-circuit for each telephone set, the talking-circuits of the different telephone sets being in part coincident with the other, and each said talking-circuit being in part coincident with a signaling-circuit; and means for supplying the current necessary for operating said telephone sets, said means being independent of and distinct from the means employed for furnishing the current necessary for operating the different signal-receiving means.

19. An electric signaling apparatus comprising

ing an electromagnet for operating a signal, independently - acting non - tuned reactive means for preventing the operation of the said electromagnet upon energization of the said means, said means including an impedance-coil, 70 and means for causing said energization.

20. A party-line telephone system comprising a plurality of signal-receiving means, at least one of said means including an electromagnet for operating a signal, independently- 75 acting non-tuned reactive means for preventing the operation of the said electromagnet upon energization of the said electromagnet upon energization of the said means, said means including an impedance-coil, 80 said system also comprising means for causing said energization; and a telephone set allotted to each signal-receiving means and designated by the signal given thereby, together with a talking-circuit for each telephone set, the talking-circuits of the different telephone sets being in part coincident with each other, and each talking-circuit being in part coincident with a signaling-circuit; and means for supplying the current necessary for operating said 90 telephone sets, said means being independent of and distinct from the means employed for furnishing the current necessary for operating the different signal-receiving means.

21. An electric signaling apparatus comprising a polarized electromagnet for operating a signal, independently-acting non-tuned reactive means for preventing the operation of the said electromagnet upon energization of the said means, said means including an impedance-coil, 95 and means for causing said energization.

22. A party-line telephone system comprising a plurality of signal-receiving means, at least one of said means including a polarized 105 electromagnet for operating a signal, independently-acting non-tuned reactive means for preventing the operation of the said electromagnet upon energization of the said reactive means, said reactive means including an impedance-coil, 110 said system also comprising means for causing said energization; and a telephone set allotted to each signal-receiving means and designated by the signal given thereby, together with a talking-circuit for 115 each telephone set, the talking-circuits of the different telephone sets being in part coincident with each other, and each said talking-circuit being in part coincident with a signaling-circuit; and means for supplying the current necessary for operating said telephone sets, 120 said means being independent of and distinct from the means employed for furnishing the current necessary for operating the different signal-receiving means.

23. An electric signaling apparatus comprising an electromagnet for operating a signal responsive to alternating currents, an armature for said electromagnet, an auxiliary electromagnet inductively associated with said ar- 125

130

- mature for controlling the operation of the aforesaid electromagnet, and means associated with the said auxiliary electromagnet for governing the operation thereof.
- 5 24. A party-line telephone system comprising a plurality of signal-receiving means, at least one of said means including an electromagnet for operating a signal responsive to alternating currents, an armature for said 10 electromagnet, an auxiliary electromagnet inductively associated with said armature for controlling the operation of the aforesaid electromagnet, and means associated with the said auxiliary electromagnet for governing the 15 operation thereof, said system also comprising means for furnishing current for operating said signal-receiving means; and a telephone set allotted to each signal-receiving means and designated by the signal given 20 thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different 25 signal-receiving means.
25. An electric signaling apparatus comprising an electromagnet and an armature for operating a signal responsive to alternating currents, an auxiliary electromagnet for locking the armature in position, and means for preventing the operation of the said electromagnet upon energization of the said auxiliary electromagnet, together with means for energizing the auxiliary magnet said magnets 30 being connected in parallel.
26. A party-line telephone system comprising a plurality of signal-receiving means, at least one of said means including an electromagnet and an armature for operating a signal 35 responsive to alternating currents, an auxiliary electromagnet for locking the armature in position, and means for preventing the operation of the said electromagnet upon energization of the said auxiliary electromagnet, together with means for energizing the auxiliary magnet said magnets 40 being connected in parallel.
- 45 27. An electric signaling apparatus comprising means for operating a signal responsive to alternating currents, an auxiliary electromagnet for locking the armature in position, and means for preventing the operation of the said electromagnet upon energization of the said auxiliary electromagnet, together with means for energizing the auxiliary magnet; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.
- 50 28. A party-line telephone system comprising a plurality of signal-receiving means, at least one of said means including an electromagnet and an armature for operating a signal responsive to alternating currents, an auxiliary electromagnet for locking the armature in position, and reactance in circuit with the said auxiliary electromagnet for effecting the operation of the said auxiliary electromagnet to lock the armature upon energization of the circuit including the said auxiliary electromagnet, together with means for energizing the auxiliary magnet.
- 55 29. An electric signaling apparatus comprising means for operating a signal responsive to alternating currents, an independently-acting permanently-closed non-tuned reactive shunt about said means, for preventing the operation of said means to actuate the signal upon operative energization of said shunt-circuit, together with means for energizing the shunt.
- 60 30. A party-line telephone system comprising a plurality of signal-receiving means, at least one of said means including means for operating a signal responsive to alternating currents, an independently-acting permanently-closed non-tuned reactive shunt about said means, for preventing the operation of said means to actuate the signal upon operative energization of said shunt-circuit, said system also comprising means for energizing the shunt; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means em-

ployed for furnishing the current necessary for operating the different signal-receiving means.

31. An electric signaling apparatus comprising means for operating a signal responsive to alternating currents, an independently-acting permanently-closed reactive shunt about said means, for preventing the operation of said means to actuate the signal upon operative energization of said shunt-circuit, together with means for energizing the shunt.

32. A party-line telephone system comprising a plurality of signal-receiving means, at least one of said means including means for operating a signal responsive to alternating currents, and an independently-acting permanently-closed reactive shunt about said means, for preventing the operation of said means to actuate the signal upon operative energization of said shunt-circuit, said system also comprising means for energizing the shunt; and a telephone set allotted to each signal-receiving means and designated by the signal given thereby, together with a talking-circuit for each telephone set, the talking-circuits of the different telephone sets being in part coincident with each other, and each said talking set being in part coincident with a signaling-circuit; and means for supplying the current necessary for operating said telephone sets, said means being independent of and distinct from the means employed for furnishing the current necessary for operating the different signaling-receiving means.

35. 33. An electric signaling apparatus comprising a polarized electromagnet for operating a signal responsive to alternating currents, an independently-acting permanently-closed reactive shunt associated with the circuit of the said electromagnet, for preventing the operation of the electromagnet to actuate the signal upon operative energization of said shunt-circuit, together with means for energizing the shunt.

45. 34. A party-line telephone system comprising a plurality of signal-receiving means, at least one of said means including a polarized electromagnet for operating a signal responsive to alternating currents, an independently-acting permanently-closed reactive shunt associated with the circuit of the said electromagnet, for preventing the operation of the electromagnet to actuate the signal upon operative energization of said shunt-circuit, said system also comprising means for energizing the shunt; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of

and distinct from the means employed for furnishing the current necessary for operating the different signal-receiving means.

35. A signaling system comprising an electric circuit, means for impressing alternating currents of different electrical character independently upon said circuit, a signal-receiving device connected with said circuit and responsive to alternating currents of a certain electrical character, a second signal-receiving device also associated with the same circuit and responsive to alternating currents of a different electrical character, and non-tuned reactive means associated with the second signal-receiving device, for preventing actuation thereof by alternating currents of an electrical character, which are adapted to operate the first-foresaid device, the different signal-receiving means being each adapted and designed independently of any signaling action of the other to perform its intended function of giving a signal to attract attention.

36. A party-line telephone system comprising an electric circuit, means for impressing alternating currents of different electrical character independently upon said circuit, signal-receiving means connected with said circuit and responsive to alternating currents of a certain electrical character, a second signal-receiving means also associated with the same circuit and responsive to alternating currents of a different electrical character, and non-tuned reactive means associated with the second signal-receiving means, for preventing actuation thereof by alternating currents of an electrical character adapted to operate the first-foresaid means; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

37. A signaling system comprising an electric circuit, a plurality of signal-receiving devices connected with the said circuit, means for impressing alternating currents upon the said circuit, means for including the first-foresaid means in the said circuit to operate one of the signal-receiving devices, and means for including non-tuned reactance in circuit with the first-foresaid means and the said circuit, whereby another of the said signals may be operated.

38. A party-line telephone system comprising an electric circuit a plurality of signal-receiving means connected with said circuit, means for impressing alternating currents

upon the said circuit, devices for including the last-mentioned means in the said circuit to operate one of the signal-receiving means, and means for including non-tuned reactance in circuit with the last-mentioned means and the said circuit, whereby another of the said signals may be operated; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

39. A signaling system comprising an electric circuit, means for selectively impressing alternating currents of different electrical character independently upon said circuit, a signal-receiving device connected with said circuit, non-tuned reactive means in circuit with said signal-receiving device, whereby said signal-receiving device is responsive to alternating currents of certain electrical character, a second signal-receiving device responsive to alternating currents of a different electrical character, and non-tuned reactive means associated with the second signal-receiving device for preventing actuation thereof by alternating currents of an electrical character, which are adapted to operate the first-aforesaid device.

40. A party-line telephone system comprising an electric circuit means for selectively impressing alternating currents of different electrical character independently upon said circuit, a signal-receiving means connected with said circuit, non-tuned reactive means in circuit with said signal-receiving means, whereby said signal-receiving means is responsive to alternating currents of certain electrical character, a second signal-receiving means responsive to alternating currents of a different electrical character, and non-tuned reactive means associated with the second signal-receiving means for preventing actuation thereof by alternating currents of an electrical character, adapted to operate the first-aforesaid means; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

for operating the different signal-receiving means.

41. A signaling system comprising an electric circuit, means for impressing alternating currents of different electrical character independently upon said circuit, a signal-receiving device connected with said circuit, non-tuned reactance in series with said signal-receiving device, whereby said signal-receiving device is responsive to alternating currents of certain electrical character, a second signal-receiving device responsive to alternating currents of a different electrical character, and non-tuned reactive means associated with the second signal-receiving device for preventing actuation thereof by alternating currents of an electrical character which are adapted to operate the first-aforesaid device.

42. A party-line telephone system comprising an electric circuit, means for impressing alternating currents of different electrical character independently upon said circuit, a signal-receiving means connected with said circuit, non-tuned reactance in series with said signal-receiving means, whereby said signal-receiving means is responsive to alternating currents of certain electrical character, a second signal-receiving means responsive to alternating currents of a different electrical character, and non-tuned reactive means associated with the second signal-receiving means for preventing actuation thereof by alternating currents of an electrical character adapted to operate the first-aforesaid device; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

43. A signaling system comprising an electric circuit, means for selectively impressing alternating currents of different electrical character upon said circuit, a signal-receiving device, connected with said circuit, non-tuned reactive means associated with said signal-receiving device whereby said signal-receiving device is responsive to alternating currents of certain electrical character, a second signal-receiving device comprising an electromagnet for operating the signal, and a reactive circuit for preventing the operation of the said electromagnet upon sufficient energization of said reactive circuit, whereby the said last-mentioned signal-receiving device is responsive to alternating currents of a different electrical character, together with means for operatively energizing the reactive circuit.

44. A party-line telephone system comprising an electric circuit, means for selectively impressing alternating currents of different electrical character upon said circuit, a signal-receiving means connected with said circuit, non-tuned reactive means associated with said signal-receiving means, whereby said signal-receiving means is responsive to alternating currents of certain electrical character, a second signal-receiving means comprising an electromagnet for operating a signal, and a reactive circuit for preventing the operation of the said electromagnet upon sufficient energization of said reactive circuit, whereby the said last-mentioned signal-receiving means is responsive to alternating currents of a different electrical character, together with means for operatively energizing the reactive circuit; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

45. A signaling system comprising an electric circuit, means for impressing alternating currents of different electrical character independently upon said circuit, a signal-receiving device connected with said circuit, non-tuned reactance in series with said signal-receiving device, whereby said signal-receiving device is responsive to alternating currents of certain electrical character, a second signal-receiving device comprising an electromagnet for operating the signal, and non-tuned reactive means for preventing the operation of the said electromagnet upon energization of said reactive means, whereby the said second signal-receiving device is responsive to alternating currents of a different electrical character.

46. A party-line telephone system comprising an electric circuit, means for impressing alternating currents of different electrical character independently upon said circuit, a signal-receiving means connected with said circuit, non-tuned reactance in series with said signal-receiving device, whereby said signal-receiving means is responsive to alternating currents of certain electrical character, a second signal-receiving means comprising an electromagnet for operating a signal, and non-tuned reactive means for preventing the operation of the said electromagnet upon energization of said reactive means, whereby the said second signal-receiving means is responsive to alternating currents of a different elec-

trical character; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

47. A signaling system comprising an electric circuit, means for impressing alternating currents of different electrical character independently upon said circuit, a signal-receiving device connected with said circuit, non-tuned reactive means in circuit with said signal-receiving device, whereby said signal-receiving device is responsive to alternating currents of certain electrical character, and a second signal-receiving device comprising a polarized electromagnet for operating the signal and reactive means for preventing the operation of the said electromagnet upon energization of said reactive means, whereby the said second signal-receiving device is responsive to alternating currents of a different electrical character.

48. A party-line telephone system comprising an electric circuit, means for impressing alternating currents of different electrical character independently upon said circuit, a signal-receiving means connected with said circuit, non-tuned reactive means in circuit with said signal-receiving device, whereby said signal-receiving means is responsive to alternating currents of certain electrical character, and a second signal-receiving device comprising a polarized electromagnet for operating a signal, and reactive means for preventing the operation of the said electromagnet upon energization of said reactive means, whereby the said second signal-receiving means is responsive to alternating currents of a different electrical character; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

49. A signaling system comprising an electric circuit, means for impressing alternating currents of different electrical character independently upon said circuit, a signal-receiving

- device connected with said circuit, reactive means in circuit with said signal-receiving device, whereby said signal-receiving device is responsive to alternating currents of certain electrical character, and a second signal-receiving device comprising an electromagnet and an armature for operating the signal, an auxiliary electromagnet for locking the armature in position, and means for preventing the operation of the said electromagnet upon energization of the said auxiliary electromagnet, whereby the said last-mentioned signal-receiving device is responsive to alternating currents of a different electrical character.
50. A party-line telephone system comprising an electric circuit, means for impressing alternating currents of different electrical character independently upon said circuit, a signal-receiving means connected with said circuit, reactive means in circuit with said signal-receiving means, whereby said signal-receiving means is responsive to alternating currents of certain electrical character, and a second signal-receiving means comprising an electromagnet and an armature for operating a signal, an auxiliary electromagnet for locking the armature in position, and means for preventing the operation of the said electromagnet upon energization of the said auxiliary electromagnet, whereby the said last-mentioned signal-receiving means is responsive to alternating currents of a different electrical character; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone set, said means being independent of and distinct from the means employed for furnishing the current necessary for operating the different signal-receiving means.
51. A signaling system comprising an electric circuit, means for impressing alternating currents of different electrical character independently upon said circuit, a signal-receiving device connected with said circuit, reactance in series with said signal-receiving device, whereby said signal-receiving device is responsive to alternating currents of certain electrical character, and a second signal-receiving device comprising an electromagnet and an armature for operating the signal, an auxiliary electromagnet for locking the armature in position, and means for preventing the operation of the said electromagnet upon energization of the said auxiliary electromagnet, whereby the said last-mentioned signal-receiving device is responsive to alternating currents of a different electrical character.
52. A party-line telephone system comprising

ing an electric circuit, means for impressing alternating currents of different electrical character independently upon said circuit, a signal-receiving means connected with said circuit, reactance in series with said signal-receiving means, whereby said signal-receiving means is responsive to alternating currents of certain electrical character, and a second signal-receiving means comprising an electromagnet and an armature for operating a signal, an auxiliary electromagnet for locking the armature in position, and means for preventing the operation of the said electromagnet upon energization of the said auxiliary electromagnet whereby the said last-mentioned signal-receiving means is responsive to alternating currents of a different electrical character; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone set, said means being independent of and distinct from the means employed for furnishing the current necessary for operating the different signal-receiving means.

53. A signaling system comprising an electric circuit, means for impressing alternating currents of different electrical character independently upon said circuit, a signal-receiving device connected with said circuit, reactive means in circuit with said signal-receiving device, whereby said signal-receiving device is responsive to alternating currents of certain electrical character, a second signal-receiving device comprising an electromagnet and an armature, an auxiliary electromagnet for locking the armature in position, and an impedance-coil included in circuit with the said auxiliary electromagnet for effecting the operation of said auxiliary electromagnet to lock the armature upon neutralization of reactance in the said impedance-coil, whereby the said last-mentioned signal-receiving device is responsive to alternating currents of a different electrical character.

54. A party-line telephone system comprising an electric circuit, means for impressing alternating currents of different electrical character independently upon said circuit, a signal-receiving means connected with said circuit, reactive means in circuit with said signal-receiving means, whereby said signal-receiving means is responsive to alternating currents of certain electrical character, a second signal-receiving means comprising an electromagnet and an armature, an auxiliary electromagnet for locking the armature in position, and an impedance-coil included in circuit with the said auxiliary electromagnet

for effecting the operation of said auxiliary electromagnet to lock the armature upon neutralization of reactance in the said impedance-coil, whereby the said last-mentioned signal-receiving means is responsive to alternating currents of a different electrical character; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

55. A signaling system comprising an electric circuit, means for impressing alternating currents of different electrical character independently upon said circuit, a signal-receiving device connected with said circuit, reactance in series with said signal-receiving device, whereby said signal-receiving device is responsive to alternating currents of certain electrical character, and a second signal-receiving device comprising an electromagnet 30 and an armature, an auxiliary electromagnet for locking the armature in position, and an impedance-coil included in circuit with the said auxiliary electromagnet for effecting the operation of the said auxiliary electromagnet 35 to lock the armature upon neutralization of reactance in the said impedance-coil, whereby the said last-mentioned signal-receiving device is responsive to alternating currents of a different electrical character.

56. A party-line telephone system comprising an electric circuit, means for impressing alternating currents of different electrical character independently upon said circuit, a signal-receiving means connected with said circuit, reactance in series with said signal-receiving means, whereby said signal-receiving means is responsive to alternating currents of certain electrical character, and a second signal-receiving means comprising an electromagnet and an armature, an auxiliary electromagnet for locking the armature in position, and an impedance-coil included in circuit with the said auxiliary electromagnet for effecting the operation of the said auxiliary electromagnet to lock the armature upon neutralization of reactance in the said impedance-coil, whereby the said last-mentioned signal-receiving means is responsive to alternating currents of a different electrical character; and a telephone set allotted to each signal-receiving means and designated by the signal given thereby, together with a talking-circuit for each telephone set, the talking-circuits of the different telephone sets being in part coincident with each other, and each said

talking-circuit being in part coincident with a signaling-circuit; and means for supplying the current necessary for operating said telephone sets, said means being independent of and distinct from the means employed for furnishing the current necessary for operating the different signal-receiving means.

57. An electric signaling apparatus comprising a signal responsive to alternating currents, a polarized electromagnet for operating said signal, and a non-tuned independently-acting reactive shunt-circuit associated with the electric circuit of the said electromagnet, for preventing the operation of said electromagnet to actuate the signal.

58. A party-line telephone system comprising a plurality of signal-receiving means, at least one of said means including a signal responsive to alternating currents, a polarized electromagnet for operating said signal, and a non-tuned independently-acting reactive shunt-circuit associated with the electric circuit of the said electromagnet, for preventing the operation of the said electromagnet to actuate the signal upon sufficient energization of said shunt-circuit by alternating current, said system also comprising means for furnishing the current for operating said signal-receiving means; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

59. An electric signaling apparatus comprising a signal responsive to alternating current, a polarized electromagnet for operating said signal, a reactive shunt-circuit associated with the electric circuit of the said electromagnet, for preventing the operation of said electromagnet to actuate the signal upon sufficient energization of said shunt-circuit by alternating current, and means for supplying said current.

60. A party-line telephone system comprising a plurality of signal-receiving means, at least one of said means including a signal responsive to alternating current, a polarized electromagnet for operating said signal, a reactive shunt-circuit associated with the circuit of the said electromagnet, for preventing the operation of said electromagnet to actuate the signal upon sufficient energization of said shunt-circuit by alternating current, said system also comprising means for supplying said current; and a telephone set allotted to each signal-receiving means and designated by the signal given thereby, together with a talking-

- circuit for each telephone set, the talking-circuits of the different telephone sets being in part coincident with each other, and each said talking-circuit being in part coincident with 5 a signaling-circuit; and means for supplying the current necessary for operating said telephone sets, said means being independent of and distinct from the means employed for furnishing the current necessary for operating the different signal-receiving means.
61. A signaling system comprising an electric circuit, source of current and means for supplying and impressing alternating currents of different electrical character independently upon said circuit, a signal-receiving device connected with said circuit and responsive to alternating current of a certain electrical character, a second signal-receiving device responsive to alternating currents of a different electrical character, and non-tuned reactive means associated with the second signal-receiving device, for preventing the actuation thereof by alternating currents of an electrical character which are adapted to operate the first-mentioned device, the different signal-receiving means being each adapted and designed independently of any signaling action of the other to perform its intended function of giving a signal to attract attention.
62. A party-line telephone system comprising an electric circuit, means for supplying and impressing alternating currents of different electrical character independently upon said circuit, a signal-receiving means connected with said circuit and responsive to alternating current of a certain electrical character, a second signal-receiving means responsive to alternating currents of a different electrical character, and non-tuned reactive means associated with the second signal-receiving means, for preventing the actuation thereof by alternating currents of an electrical character which are adapted to operate the first-mentioned signal-receiving means; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.
63. A signaling system comprising an electric circuit, source of current means for impressing alternating currents of different electrical character independently upon said circuit, a signal-receiving device connected with said circuit and responsive to alternating current of a certain electrical character, a second signal-receiving device responsive to alternating currents of a different electrical character, said last-mentioned signal-receiving device including a shunt-circuit for precluding the actuation thereof by alternating currents of an electrical character which are adapted to operate the first-mentioned device.
64. A party-line telephone system comprising an electric circuit, means for impressing alternating currents of different electrical character independently upon said circuit, a signal-receiving means connected with said circuit and responsive to alternating current of a certain electrical character, a second signal-receiving means responsive to alternating currents of a different electrical character, said last-mentioned signal-receiving means including a shunt-circuit for precluding the actuation thereof by alternating currents of an electrical character adapted to operate the first-mentioned signal-receiving means; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.
65. A signaling system comprising an electric circuit, switching mechanism for selectively impressing alternating currents of different electrical character independently upon said circuit, a signal-giving device connected with said circuit, an impedance device in circuit with said signal-giving device, whereby the signal-receiving apparatus thus provided is responsive to alternating currents of a certain electrical character, a second signal-receiving apparatus responsive to alternating currents of a different electrical character, said last-mentioned signal-receiving apparatus including an impedance device also associated with the same circuit, for preventing the actuation thereof by alternating current of a character adapted to operate the first-mentioned signal-receiving apparatus, the signal-receiving apparatus thus provided being non-tuned in character, the different signal-receiving means being each adapted and designed independently of any signaling action of the other to perform its intended function of giving a signal to attract attention.
66. A party-line telephone system comprising an electric circuit, switching mechanism for selectively impressing alternating currents of different electrical character independently upon said circuit, a signal-giving means connected with said circuit, an impedance device in circuit with said signal-giving means, whereby the signal-receiving apparatus

tus thus provided is responsive to alternating currents of a certain electrical character, a second signal-receiving apparatus responsive to alternating currents of a different electrical character, said last-mentioned signal-receiving apparatus including an impedance device also associated with the same circuit, for preventing the actuation thereof by alternating current of a character adapted to operate the first-foresaid signal-receiving means, the signal-receiving apparatus thus provided being non-tuned in character; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

67. A signaling system comprising an electric circuit, means for selectively impressing alternating currents of different electrical character independently upon said circuit, a signal-receiving device connected with said circuit, an impedance device associated with said signal-receiving device, whereby said signal-receiving device is unresponsive to alternating currents of a certain electrical character, a second signal-receiving device unresponsive to alternating currents of a different electrical character and including an impedance device also associated with the same circuit, for permitting an actuation of the said signal-receiving device by said first-mentioned alternating currents, the first-mentioned signal-receiving apparatus thus provided being non-tuned in character, the different signal-receiving means being each adapted and designed independently of any signaling action of the other to perform its intended function of giving a signal to attract attention.

68. A party-line telephone system comprising an electric circuit, means for selectively impressing alternating currents of different electrical character independently upon said circuit, a signal-receiving means connected with said circuit, an impedance device associated with said signal-receiving means, whereby said signal-receiving means is unresponsive to alternating currents of a certain electrical character, a second signal-receiving means unresponsive to alternating currents of a different electrical character and including an impedance device, also associated with the same circuit, for permitting an actuation of the said second signal-receiving means by said certain alternating currents, the signal-receiving apparatus thus provided being non-tuned in character; and a telephone set allotted

to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

69. A signaling system in which alternating currents of different electrical character are projected onto the line, one at a time, and in which the line is normally free from signaling-current, the system including a signal-receiving apparatus alone responsive to an alternating current of a predetermined character, and another signal-receiving apparatus alone responsive to alternating current of a different character, the signal-receiving apparatus being of a non-tuned character, in one case, at least, the different signal-receiving means being each adapted and designed independently of any signaling action of the other to perform its intended function of giving a signal to attract attention.

70. A party-line telephone system in which alternating currents of different electrical character are projected onto the line, one at a time, and in which the line is normally free from signaling-current, the system including a signal-receiving means alone responsive to an alternating current of a predetermined character, and another signal-receiving means alone responsive to alternating current of a different character, the signal-receiving means being of a non-tuned character in one case at least; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

71. The combination of a plurality of signal-receiving devices, each included in a signal-receiving apparatus responsive to alternating current of predetermined character, a line conductor to which all of said devices are connected, and means for impressing alternating currents, each independent of the other, and of a predetermined character, upon the said line, the signal-receiving apparatus being of a non-tuned character in each case, the different signal-receiving means being each adapted and designed independently of any signaling

action of the other to perform its intended function of giving a signal to attract attention.

72. The combination of a plurality of signal-receiving devices, each included in a signal-receiving means alone responsive to alternating current of predetermined character, a line conductor to which all of said devices are connected, and means for impressing alternating currents each independently of the other, and of a predetermined character, upon the said line, the signal-receiving means being of a non-tuned character in each case; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

73. A signaling system in which alternating currents of different electrical character are projected onto the line, one at a time, and in which the line is normally free from signaling-current, the system including a signal-receiving apparatus responsive to alternating current of a predetermined character, and another signal-receiving apparatus responsive to alternating current of a different character, each signal-receiving apparatus including suitable reactive means, and the signal-receiving apparatus being non-tuned in character in each case.

74. A party-line telephone system in which alternating currents of different electrical character are projected onto the line, one at a time, and in which the line is normally free from signaling-current, the system including a signal-receiving means responsive to alternating current of a predetermined character, and another signal-receiving means responsive to alternating current of a different character, each signal-receiving means including suitable reactive means, and the signal-receiving means being non-tuned in character in each case; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

75. The combination of a plurality of signal-receiving devices, each included in a signal-

receiving apparatus responsive to alternating current of predetermined character, a line conductor to which all of said devices are connected, and means for impressing alternating currents each independent of the other, and of a predetermined character, upon the line, at least one signal-receiving apparatus comprising reactive means and a signal connected in series, and the signal-receiving apparatus being non-tuned in at least one case.

76. The combination of a plurality of signal-receiving devices each included in a signal-receiving means responsive to alternating current of predetermined character, a line conductor to which all of said devices are connected, and means for impressing alternating currents, each independently of the other, and of a predetermined character, upon the line, at least one signal-receiving means comprising reactive means and a signal connected in series, and the signal-receiving means being non-tuned in at least one case; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

77. The combination of a plurality of signal-receiving devices, each included in a signal-receiving apparatus alone responsive to fluctuating current of a predetermined character, a line conductor to which all of said devices are connected, and means for impressing fluctuating currents each independent of the other, and of a predetermined character, upon the line, the signal-receiving apparatus being non-tuned in character in each case, and also relatively selective in character with respect to the different currents, the different signal-receiving means being each adapted and designed independently of any signaling action of the other to perform its intended function of giving a signal to attract attention.

78. The combination of a plurality of signal-receiving devices, each included in a signal-receiving means alone responsive to fluctuating current of a predetermined character, a line conductor to which all of said devices are connected, and means for impressing fluctuating currents, each independently of the other, and of a predetermined character, upon the line, the signal-receiving means being non-tuned in character in each case, and also relatively selective in character with respect to the different currents; and a telephone set allotted to each signal-receiving means and designated by the signal given thereby, to-

gether with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

79. The combination of an electric circuit, a plurality of substations connected in parallel in said circuit, each substation being equipped with non-tuned signal-receiving apparatus adapted alone to respond to alternating current of a predetermined character, and means for projecting alternating currents of different character upon said circuit for the purpose of selectively operating the signals at said stations, the different signal-receiving means being each adapted and designed independently of any signaling action of the other to perform its intended function of giving a signal to attract attention.

80. The combination of an electric circuit, a plurality of substations connected in parallel in said circuit, each substation being equipped with non-tuned signal-receiving means adapted alone to respond to alternating current of a predetermined character, and means for projecting alternating currents of different character upon said circuit for the purpose of selectively operating the signals at said stations; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

81. The combination of an electric circuit, a plurality of substations connected in parallel in said circuit, each substation being equipped with non-tuned signal-receiving apparatus adapted alone to respond to alternating currents of a certain character, the apparatus at each station including a signal and suitable reactive means, the reactive means at each station being adapted to prevent all except the right current from causing the operation of its associated signal, and means for projecting alternating currents of different character onto said circuit for the purpose of selectively operating said signals, the different signal-receiving means being each adapted and designed independently of any signaling action of the other to perform its

intended function of giving a signal to attract attention.

82. The combination of an electric circuit, a plurality of substations connected in parallel in said circuit, each substation being equipped with non-tuned signal-receiving means adapted alone to respond to alternating currents of a certain character, the apparatus at each station including a signal and suitable reactive means, the reactive means at each station being adapted to prevent all except the right current from causing the operation of its associated signal, and means for projecting alternating currents of different character onto said circuit for the purpose of selectively operating said signals; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

83. The combination of an electric circuit, a plurality of parallel branches in said circuit, a signal associated with each branch, reactive means in each branch, the reactive means in each case being adapted to prevent an effective passage through its allotted signal of all currents except those intended and adapted to cause the operation of such signal, and means for projecting alternating currents of different character onto said circuit for the purpose of selectively operating said signals, the signal-receiving apparatus thus associated with at least one branch being non-tuned in character, the different signal-receiving means being each adapted and designed independently of any signaling action of the other to perform its intended function of giving a signal to attract attention.

84. The combination of an electric circuit, a plurality of parallel branches in said circuit, a signal associated with each branch, reactive means in each branch, the reactive means in each case being adapted to prevent an effective passage through its allotted signal of all currents except those intended and adapted to cause the operation of such signal, and means for projecting alternating currents of different character onto said circuit for the purpose of selectively operating said signals, the signal-receiving means thus associated with at least one branch being non-tuned in character; and a telephone set allotted to each signal-receiving means and designated by the signal given thereby, together with a talking-circuit for each telephone set, the talking-circuits of the different telephone sets being in

part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

85. The combination of a plurality of parallel branch circuits including a line-wire which is common to all of said circuits, reactive means in each circuit, an electric bell allotted to each circuit, the reactive means in each case being adapted to prevent an effective passage through its allotted signal of all currents except those intended and adapted for operating its allotted bell, and means for projecting alternating currents of different character onto said line for the purpose of selectively ringing said bells, the signal-receiving apparatus thus associated with each branch being non-tuned in character, the different signal-receiving means being each adapted and designed independently of any signaling action of the other to perform its intended function of giving a signal to attract attention.

86. The combination of a plurality of parallel branch circuits including a line-wire which is common to all of said circuits, reactive means in each circuit, an electric bell allotted to each circuit, the reactive means in each case being adapted to prevent an effective passage through its allotted bell of all currents except those intended and adapted for operating its allotted bell, and means for projecting alternating currents of different character onto said line for the purpose of selectively ringing said bells, the signal-receiving means thus associated with each branch being non-tuned in character; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

87. The combination of a plurality of parallel circuits including a line-wire common to all of said circuits, a signaling device allotted to each circuit, a reactive device in each circuit adapted in each case to preclude an effective passage through its allotted signaling device of all currents except those intended and adapted to cause the operation of such signaling device, and means for projecting alternating currents of different character upon said line-wire for the purpose of selectively operating the signals, the signal-receiving apparatus thus provided for each circuit being non-tuned in character, the different signal-receiving means being each adapted and designed independently of any signaling action of the other to perform its intended function of giving a signal to attract attention.

88. The combination of a plurality of parallel circuits including a line-wire common to all of said circuits, a signaling device allotted to each circuit, a reactive device in each circuit adapted in each case to preclude an effective passage through its allotted signaling device of all currents except those intended and adapted to cause the operation of such signaling device, and means for projecting alternating currents of different character upon said line-wire for the purpose of selectively operating the signals, the signal-receiving means thus provided for each circuit being non-tuned in character; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

89. The combination of an electric circuit, a non-tuned signal-receiving apparatus connected with said circuit and responsive alone to all alternating currents above a predetermined point of variation, a second signal-receiving apparatus connected with said circuit and responsive alone to all alternating currents below a predetermined point of variation, and means for projecting alternating currents of different character upon said circuit for the purpose of selectively operating the signals included in said apparatus, the different signal-receiving means being each adapted and designed independently of any signaling action of the other to perform its intended function of giving a signal to attract attention.

90. The combination of an electric circuit, a non-tuned signal-receiving means connected with said circuit and responsive alone to all alternating currents above a predetermined point of variation, a second signal-receiving means connected with said circuit and responsive alone to all alternating currents below a predetermined point of variation, and means for projecting alternating currents of different character upon said circuit for the purpose of selectively operating the signals included in said receiving means; and a telephone set allotted to each signal-receiving means and des-

ignated by the signal given thereby, together with a talking-circuit for each telephone set, the talking-circuits of the different telephone sets being in part coincident with each other, 5 and each said talking-circuit being in part coincident with a signaling-circuit; and means for supplying the current necessary for operating said telephone sets, said means being independent of and distinct from the means employed for furnishing the current necessary 10 for operating the different signal-receiving means.

91. An electric signaling system comprising a circuit having a plurality of parallel non-tuned reactive branches, there being a suitable translating device allotted to each branch, and means for projecting vibratory currents of different electrical character onto said circuit, said means and reactive branches being adapted, by reason of the different degrees of impedance offered by the branches to the different currents, to conjointly vary the relative current-flow through said translating devices, and each translating device being responsive 25 to its allotted character of current and no other, whereby the different currents may be used at will for selectively operating the different translating devices, the different signal-receiving means being each adapted and designed independently of any signaling action of the other to perform its intended function of giving a signal to attract attention.

92. A party-line telephone system comprising a circuit having a plurality of parallel non-tuned reactive branches, there being a suitable translating device allotted to each branch, and means for projecting vibratory currents of different electrical character onto said circuit, said means and reactive branches being adapted, by reason of the different degrees of impedance offered by the branches to the different currents, to conjointly vary the relative current-flow through said translating devices, each signal-receiving means being responsive to its allotted character of current and no other, whereby the different currents may be used at will for selectively operating the different translating devices; and a telephone set allotted to each signal-receiving 45 means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary 50 for operating the different signal-receiving means.

93. A selective signaling system comprising a line-circuit having a plurality of parallel non-tuned reactive branches, signal-receiving apparatus allotted to each branch, and means

for impressing alternating currents of different electrical character upon said circuit, the signal-receiving apparatus of each branch being, by reason of the particular character or disposition of the reactance of such branch, 70 responsive to only one of the different currents employed, the different signal-receiving means being each adapted and designed independently of any signaling action of the other to perform its intended function of giving a 75 signal to attract attention.

94. A party-line telephone system comprising a line-circuit having a plurality of parallel non-tuned reactive branches, signal-receiving means allotted to each branch, and means for 80 impressing alternating currents of different electrical character upon said circuit, the signal-receiving means of each branch being, by reason of the particular character or disposition of the reactance of such branch, responsive to only one of the different currents employed; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating 95 said telephone sets, said means being independent of and distinct from the means employed for furnishing the current necessary for operating the different signal-receiving means.

95. An electric signaling system comprising a circuit having a plurality of parallel branches, and means for projecting vibratory currents of different character upon said circuit, there being a non-tuned reactive signal-receiving apparatus allotted to each branch, each apparatus including a translating device, each signal-receiving apparatus being responsive to its allotted character of current and no other, and the reactive means of said apparatus and the said means for projecting currents being adapted, by reason of the different degrees of impedance offered by the reactive means to the different currents, to conjointly vary the relative current-flow 115 through said translating devices, whereby the different currents may be employed at will for selectively operating said devices, the different signal-receiving means being each adapted and designed independently of any 120 signaling action of the other to perform its intended function of giving a signal to attract attention.

96. A party-line telephone system comprising a circuit having a plurality of parallel branches, and means for projecting vibratory currents of different character upon said circuit, there being a non-tuned reactive signal-receiving means allotted to each branch, each signal-receiving means including a translat- 125

130

- ing device responsive to its allotted character of current and no other, and the reactive means of said receiving means and the said means for projecting currents being adapted, 5 by reason of the different degrees of impedance offered by the reactive means to the different currents, to conjointly vary the relative current-flow through said translating devices, whereby the different currents may be 10 employed at will for selectively operating said devices; and a telephone set allotted to each signal-receiving means and designated by the signal given thereby, together with a talking-circuit for each telephone set, the 15 talking-circuits of the different telephone sets being in part coincident with each other, and each said talking-circuit being in part coincident with a signaling-circuit; and means for supplying the current necessary for operating 20 said telephone sets, said means being independent of and distinct from the means employed for furnishing the current necessary for operating the different signal-receiving means.
- 25 97. An electric signaling system comprising signal-transmitting apparatus for sending vibratory currents of different character, and non-tuned reactive signal-receiving apparatus suitably connected with said signal-transmitting apparatus, said signal-receiving apparatus including a plurality of electromagnets and means whereby each magnet when sufficiently energized produces a signal, each signal-receiving apparatus being responsive to 30 its allotted character of current and no other, and the said transmitting and receiving apparatus being adapted, by reason of the different degrees of impedance offered by the receiving apparatus to vibratory currents of 35 different character, to conjointly increase and decrease the relative flow of current in the different magnets, whereby the different currents may be used to selectively produce the different signals, the different signal-receiving 40 means being each adapted and designed independently of any signaling action of the other to perform its intended function of giving a signal to attract attention.
- 45 98. A party-line telephone system comprising signal-transmitting apparatus for sending vibratory currents of different character, and a plurality of non-tuned reactive signal-receiving means suitably connected with said signal-transmitting apparatus, said signal-receiving means including a plurality of electromagnets and means whereby each magnet when sufficiently energized produces a signal, each signal-magnet being responsive to its allotted character of current and no other, 50 and the said transmitting and receiving apparatus being adapted, by reason of the different degrees of impedance offered by the receiving apparatus to vibratory currents of different character, to conjointly increase and decrease the relative flow of current in the 55

different magnets, whereby the different currents may be used to selectively produce the different signals; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

99. An electric signaling system comprising signal-transmitting apparatus adapted for sending vibratory currents of different reactive character, non-tuned reactive signal-receiving apparatus suitably connected with said signal-transmitting apparatus, said signal-receiving apparatus including a plurality of signal-magnets, and means whereby each magnet when sufficiently energized produces a signal, each signal-magnet being responsive to its allotted character of current and no other, and the transmitting and receiving apparatus thus provided being adapted, by reason of the different degrees of impedance offered by the receiving apparatus to vibratory currents of different character, to conjointly increase and decrease the relative flow of current in the different magnets, as the character of the current changes, whereby the different currents may be used to selectively produce the different signals, the different signal-receiving means being each adapted and designed independently of any signaling action of the other to perform its intended function of giving a signal to attract attention.

100. A party-line telephone system comprising signal-transmitting apparatus adapted for sending vibratory currents of different reactive character, a plurality of non-tuned reactive signal-receiving means suitably connected with said signal-transmitting apparatus, said signal-receiving means including a plurality of signaling-magnets, and means whereby each magnet, when sufficiently energized, produces a signal, each signal-magnet being responsive to its allotted character of current and no other, the transmitting and receiving apparatus thus provided being adapted, by reason of the different degrees of impedance offered by the receiving apparatus to vibratory currents of different character, to conjointly increase and decrease the relative flow of current in the different magnets, as the character of the current changes, whereby the different currents may be used to selectively produce the different signals; and a telephone set allotted to each signal-receiving means and designated by the signal

given thereby, together with a talking-circuit for each telephone set, the talking-circuits of the different telephone sets being in part coincident with each other, and each said 5 talking-circuit being in part coincident with a signaling-circuit; and means for supplying the current necessary for operating said telephone sets, said means being independent of and distinct from the means employed for 10 furnishing the current necessary for operating the different signal-receiving means.

101. An electric signaling system comprising a signal-transmitting apparatus adapted for sending alternating currents of different 15 character, non-tuned reactive signal-receiving apparatus suitably connected with said transmitting apparatus, said signal-receiving apparatus including a plurality of signal-magnets, and means whereby each magnet when 20 sufficiently energized produces a signal, each signal-magnet being responsive to its allotted character of current and no other, and the said transmitting and receiving apparatus being adapted, by reason of the different degrees 25 of impedance offered by the receiving apparatus to intermittent currents of different character, to conjointly increase and decrease the relative flow of current in the different magnets, whereby the different currents 30 may be used to selectively produce the different signals, the different signal-receiving means being each adapted and designed independently of any signaling action of the other to perform its intended function of giving a 35 signal to attract attention.

102. A party-line telephone system comprising a signal-transmitting apparatus adapted for sending alternating currents of different character, a plurality of non-tuned reactive 40 signal-receiving means suitably connected with said transmitting apparatus, said signal-receiving means including a plurality of signal-magnets, and means whereby each magnet when sufficiently energized produces a signal, each signal-magnet being responsive to its allotted character of current and no other, the said transmitting and receiving apparatus being adapted, by reason of the different degrees of impedance offered by the 45 receiving apparatus to vibratory or fluctuating currents of different character, to conjointly increase and decrease the relative flow of current in the different magnets, whereby the different currents may be used to selectively produce the different signals; and a telephone set allotted to each signal-receiving means and designated by the signal given thereby, together with a talking-circuit for each telephone set, the talking-circuits of the 50 different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

65

tinct from the means employed for furnishing the current necessary for operating the different signal-receiving means.

103. An electric signaling system comprising generating apparatus for supplying fluctuating currents of different electrical character, a signal-receiving device only responsive to the fluctuating currents of certain electrical character, and a second signal-receiving device only responsive to the fluctuating currents of a different electrical character, said last-mentioned signal-receiving device having non-tuned reactive means associated therewith to prevent the operation of said device by currents adapted to operate the first-mentioned signal-receiving device, the different signal-receiving means being each adapted and designed independently of any signaling action of the other to perform its intended function of giving a signal to attract attention.

104. A party-line telephone system comprising generating apparatus for supplying fluctuating currents of different electrical character, a signal-receiving means only responsive to the fluctuating currents of certain electrical character, and a second signal-receiving means only responsive to the fluctuating currents of a different electrical character, said last-mentioned signal-receiving means having non-tuned reactive means associated therewith to prevent the operation thereof by currents adapted to operate the first-mentioned signal-receiving means; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

105. An electric signaling system comprising generating apparatus for supplying fluctuating currents of different electrical character, a signal-receiving device alone responsive to the fluctuating currents of certain electrical character, and a second signal-receiving device alone responsive to the fluctuating currents of a different electrical character, said last-mentioned signal-receiving device having a non-tuned inductive element associated therewith to prevent the operation of said device by currents adapted to operate the first-mentioned signal-receiving device, the different signal-receiving means being each adapted and designed independently of any signaling action of the other to perform its intended function of giving a signal to attract attention.

106. A party-line telephone system com-

prising generating apparatus for supplying fluctuating currents of different electrical character, a signal-receiving means alone responsive to the fluctuating currents of certain electrical character, and a second signal-receiving means alone responsive to the fluctuating currents of a different electrical character, said last-mentioned signal-receiving means having a non-tuned inductive element associated therewith to prevent the operation thereof by currents adapted to operate the first-mentioned signal-receiving means; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

107. An electric signaling system comprising generating apparatus for supplying alternating currents of different electrical character, a signal-receiving device only responsive to the alternating currents of certain electrical character, and a second signal-receiving device only responsive to the alternating currents of a different electrical character, said last-mentioned signal-receiving device having a non-tuned reactive element associated therewith to prevent the operation of said device by currents adapted to operate the first-mentioned signal-receiving device, the different signal-receiving means being each adapted and designed independently of any signaling action of the other to perform its intended function of giving a signal to attract attention.

108. A party-line telephone system comprising generating apparatus for supplying alternating currents of different electrical character, a signal-receiving means only responsive to the alternating currents of certain electrical character, and a second signal-receiving means only responsive to the alternating currents of a different electrical character, said last-mentioned signal-receiving means having a non-tuned reactive element associated therewith to prevent the operation thereof by currents adapted to operate the first-mentioned signal-receiving means; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

tinct from the means employed for furnishing the current necessary for operating the different signal-receiving means.

109. An electric signaling system comprising apparatus for supplying currents of different electrical character, a signal-receiving device alone responsive to currents of certain electrical character, and a second signal-receiving device alone responsive to currents of a different electrical character and normally 70 in circuit with a non-tuned reactive element for preventing the operation thereof by currents adapted to operate the first-aforesaid device, the different signal-receiving means being each adapted and designed independently 75 of any signaling action of the other to perform its intended function of giving a signal to attract attention.

110. A party-line telephone system comprising apparatus for supplying currents of 85 different electrical character, a signal-receiving means alone responsive to currents of certain electrical character, and a second signal-receiving means alone responsive to currents of a different electrical character and normally 90 in circuit with a non-tuned reactive element for preventing the operation thereof by currents adapted to operate the first-aforesaid means; and a telephone set allotted to each signal-receiving means and designated by the 95 signal given thereby, together with a talking-circuit for each telephone set, the talking-circuits of the different telephone sets being in part coincident with each other, and each said talking-circuit being in part coincident with 100 a signaling-circuit; and means for supplying the current necessary for operating said telephone sets, said means being independent of and distinct from the means employed for furnishing the current necessary for operating 105 the different signal-receiving means.

111. An electric signaling system comprising generating apparatus for supplying fluctuating currents of different electrical character, a signal-receiving device only responsive to the fluctuating currents of certain electrical character, and a second signal-receiving device only responsive to the fluctuating currents of a different electrical character and having a non-tuned reactive element associated therewith 110 the reactance of which acts to prevent the operation of said device by currents adapted to operate the first-aforesaid device, the different signal-receiving means being each adapted and designed independently 115 of any signaling action of the other to perform its intended function of giving a signal to attract attention.

112. A party-line telephone system comprising generating apparatus for supplying 125 fluctuating currents of different electrical character, a signal-receiving means only responsive to the fluctuating currents of certain electrical character, and a second signal-receiving means only responsive to the fluctuat- 130

ing currents of a different electrical character and having a non-tuned reactive element associated therewith the reactance of which serves to prevent the operation of said means by currents adapted to operate the first-mentioned signal-receiving means; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

113. An electric signaling system comprising apparatus for supplying currents of unlike electrical character, a signal-receiving device alone responsive to currents of certain electrical character, and a second signal-receiving device alone responsive to currents of different electrical character and associated with a non-tuned reactive element the reactive character of which prevents the operation thereof by currents adapted to operate the first aforesaid device and permits the operation thereof by currents of a different electrical character, the different signal-receiving means being each adapted and designed independently of any signaling action of the other to perform its intended function of giving a signal to attract attention.

114. A party-line telephone system comprising apparatus for supplying currents of unlike electrical character, a signal-receiving means alone responsive to currents of certain electrical character, and a second signal-receiving means alone responsive to currents of different electrical character and associated with a non-tuned reactive element the reactive character of which prevents the operation thereof by currents adapted to operate the first-aforesaid means and permits the operation thereof by currents of a different electrical character; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

115. A system comprising means for selectively operating a plurality of signals, and including a selective electric signaling device

consisting of an electromagnetic signal having a non-tuned reactive element in circuit therewith the reactive effect of which controls the operation thereof, the different signal-receiving means being each adapted and designed independently of any signaling action of the other to perform its intended function of giving a signal to attract attention.

116. A party-line telephone system comprising means for selectively controlling a plurality of signals, said means including a selective electric signaling device consisting of an electromagnetic signal having a non-tuned reactive element in circuit therewith the reactive effect of which controls the operation thereof; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

117. A system comprising means of selectively operating a plurality of signals, and including a selective electric signaling device consisting of an electromagnetic signal having a non-tuned reactive element in permanent operative circuit therewith the reactive effect of which controls the operation thereof, the different signal-receiving means being each adapted and designed independently of any signaling action of the other to perform its intended function of giving a signal to attract attention.

118. A party-line telephone system comprising means of selectively controlling a plurality of signals, said means including a selective electric signaling device consisting of an electromagnetic signal having a non-tuned reactive element in permanent operative circuit therewith the reactive effect of which controls the operation thereof; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

119. A system comprising means for selectively operating a plurality of signals, and including a selective electric signaling device consisting of an electromagnetic signal having

a non-tuned reactive element in circuit therewith the choking effect of which controls the operation thereof, the different signal-receiving means being each adapted and designed 5 independently of any signaling action of the other to perform its intended function of giving a signal to attract attention.

120. A party-line telephone system comprising means for selectively controlling a plurality of signals, said means including a selective electric signaling device consisting of an electromagnetic signal having a non-tuned reactive element in circuit therewith the choking effect of which controls the operation thereof; 15 and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of 20 and distinct from the means employed for furnishing the current necessary for operating the different signal-receiving means.

121. A system comprising means for selectively operating a plurality of signals, and including a selective electric signaling device consisting of an electromagnetic signal having a non-tuned reactive element normally in circuit therewith the choking effect of which controls the operation thereof, the different signal-receiving means being each adapted and designed independently of any signaling action of the other to perform its intended function of giving a signal to attract attention.

122. A party-line telephone system comprising means for selectively controlling a plurality of signals, said means including a selective electric signaling device consisting of an electromagnetic signal having a non-tuned reactive element normally in circuit therewith the choking effect of which controls the operation thereof; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

123. An electric signaling system comprising apparatus for supplying currents of unlike electrical character, two signal-receiving devices adapted to be operated selectively by the unlike currents, and reactive apparatus associated with said devices the reactive qualities 65 of which are adapted gradually to change the

supply of current to said devices should the current change gradually from one character to another.

124. A party-line telephone system comprising apparatus for supplying currents of unlike electrical character, two signal-receiving devices adapted to be operated selectively by the unlike currents, and reactive apparatus associated with said devices the reactive qualities of which are adapted gradually to change 70 the supply of current to said devices should the current change gradually from one character to another; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the 75 current necessary for operating said telephone sets, said means being independent of and distinct from the means employed for furnishing the current necessary for operating the different signal-receiving means. 80

125. An electric signaling system comprising an electric circuit, a device for producing fluctuating currents of a certain electrical character, a device for producing fluctuating currents of a different electrical character, an 95 electrical signaling apparatus responsive to currents of said certain electrical character and decreasingly responsive should the current more nearly and gradually approach that of said different electrical character, a second signal-receiving apparatus responsive to currents of said different electrical character and decreasingly responsive should the current 100 gradually approach in character that of said certain electrical character. 105

126. A party-line telephone system comprising an electric circuit, a device for producing fluctuating currents of a certain electrical character, a device for producing fluctuating currents of a different electrical character, a 110 signal-receiving means responsive to currents of said certain electrical character and decreasingly responsive should the current more nearly and gradually approach that of said different electrical character, a second signal-receiving means responsive to currents of said different electrical character and decreasingly responsive should the current gradually approach in character that of said certain electrical character; and a telephone set allotted 115 to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for 120 supplying the current necessary for operating said telephone sets, said means being independent of and distinct from the means em- 125 130

ployed for furnishing the current necessary for operating the different signal-receiving means.

127. An electrical signaling system comprising an electric circuit, apparatus for generating fluctuating currents of different electrical character, signaling apparatus composed of two electrical signal devices responsive to currents of different electrical character, and means whereby each signal device is made constantly decreasingly liable to respond should the current gradually approach in character the operative current of the other signal device.

128. A party-line telephone system comprising an electric circuit, apparatus for generating fluctuating currents of different electrical character, signaling apparatus composed of two electrical signal devices responsive to currents of different electrical character, and means whereby each signal device is made constantly decreasingly liable to respond should the current gradually approach in character the operative current of the other signal device; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

129. The combination of a plurality of signal-receiving devices each included in a signal-receiving apparatus alone responsive to vibratory currents of predetermined character, a line conductor to which all of said devices are connected, and means for impressing vibratory currents, each independent of the other, and of a different predetermined character, upon the said line, the signal-receiving apparatus being of a non-tuned character in each case, and the signal-transmitting means including a switching device having keys corresponding to the different signal-receiving apparatus, whereby each signal-receiving device may be operated at will by merely pressing its allotted key, the different signal-receiving means being each adapted and designed independently of any signaling action of the other to perform its intended function of giving a signal to attract attention.

130. The combination of a plurality of signal-receiving devices each included in a signal-receiving means alone responsive to vibratory currents of predetermined character, a line conductor to which all of said devices are connected, and means for impressing vibratory currents, each independently of the other, and of a different predetermined character, upon

the said line, the signal-receiving means being of a non-tuned character in each case, and the signal-transmitting means including a switching device having keys corresponding to the different signal-receiving means, whereby each signal-receiving device may be operated at will by merely pressing its allotted key; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

131. A signaling system in which vibratory currents of different electrical character are projected onto the line, one at a time, and in which the line is normally free from signaling-current, the system including a signal-receiving apparatus alone responsive to vibratory currents of a predetermined character, and another signal-receiving apparatus alone responsive to vibratory current of a different character, the signal-receiving apparatus being of a non-tuned character in one case, at least, and the system also including a switching device having keys corresponding to the first and second signal-receiving apparatus, whereby either apparatus may be operated at will by pressing its allotted switch-key, the different signal-receiving means being each adapted and designed independently of any signaling action of the other to perform its intended function of giving a signal to attract attention.

132. A party-line telephone system in which vibratory currents of different electrical character are projected onto the line, one at a time, and in which the line is normally free from signaling-current, the system including a signal-receiving means alone responsive to vibratory currents of a predetermined character, and another signal-receiving means alone responsive to vibratory current of a different character, the signal-receiving means being of a non-tuned character in one case at least, and the system also including a switching device having keys corresponding to the first and second signal-receiving means, whereby either means may be operated at will by merely pressing its allotted switch-key; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone

sets, said means being independent of and distinct from the means employed for furnishing the current necessary for operating the different signal-receiving means.

- 5 133. A signaling system comprising an electric circuit, means for impressing vibratory currents of different electrical character independently upon said circuit, a signal-receiving apparatus connected with said circuit and alone responsive to vibratory currents of a certain electrical character, a second signal-receiving apparatus also associated with the same circuit and alone responsive to vibratory currents of a different electrical character, 10 there being non-tuned reactive means included in the second signal-receiving apparatus for preventing actuation thereof by vibratory currents of an electrical character which are adapted to operate the first-aforesaid apparatus, and the said means for impressing the currents including a switching device having keys corresponding to the said first and second receiving apparatus, whereby either apparatus may be operated at will by pressing 15 its allotted switch-key, the different signal-receiving means being each adapted and designed independently of any signaling action of the other to perform its intended function of giving a signal to attract attention.
- 20 134. A party-line telephone system comprising an electric circuit, means for impressing vibratory currents of different electrical character independently upon said circuit, a signal-receiving means connected with said circuit and alone responsive to vibratory currents of a certain electrical character, a second signal-receiving means also associated with the same circuit and alone responsive to vibratory currents of a different electrical character, 25 there being non-tuned reactive means included in the second signal-receiving means for preventing actuation thereof by vibratory currents of an electrical character adapted to operate the first-aforesaid signal-receiving means, and the said means for impressing the currents including a switching device having keys corresponding to the said first and second receiving apparatus, whereby either signal-receiving means may be operated at will by merely pressing its allotted 30 switch-key; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating 35 said telephone sets, said means being independent of and distinct from the means employed for furnishing the current necessary for operating the different signal-receiving means.
- 40 135. An electric signaling apparatus, com-

prising an electromagnet for operating a signal, normally non-neutralized inductive means for permitting the operation of the said electromagnet upon neutralization of inductance in the said means, and means for at will causing said neutralization. 70

136. A party-line telephone system comprising a plurality of signal-receiving means, at least one of said means including an electromagnet for operating a signal, normally non-neutralized inductive means for permitting the operation of the said electromagnet upon neutralization of inductance in the said inductive means, said system also comprising means for at will causing said neutralization; 75 and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of 80 and distinct from the means employed for furnishing the current necessary for operating the different signal-receiving means. 85

137. An electric signaling apparatus comprising a polarized electromagnet for operating a signal, normally non-neutralized inductive means for permitting the operation of the said electromagnet upon neutralization of inductance in the said means, and means for at will causing said neutralization. 90

138. A party-line telephone system comprising a plurality of signal-receiving means, at least one of said means including a polarized electromagnet for operating a signal, normally non-neutralized inductive means for 95 permitting the operation of the said electromagnet upon neutralization of inductance in the said inductive means, said system also comprising means for at will causing said neutralization; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means. 100

139. An electric signaling system comprising signal-transmitting apparatus adapted for sending vibratory or fluctuating currents of different character, and non-tuned reactive signal-receiving apparatus suitably connected with said signal-transmitting apparatus, said signal-receiving apparatus including a plu- 105 110 115 120 125 130

rality of signal-magnets, and means whereby each magnet when sufficiently energized produces a signal, each signal-magnet being responsive to its allotted character of current 5 and no other, and the said transmitting and receiving apparatus being adapted, by reason of the different degrees of impedance offered by the receiving apparatus to intermittent currents of different character, to conjointly increase and decrease the relative flow of current in the different magnets, whereby the different currents may be used to selectively produce the different signals, said signal-transmitting apparatus including a switching device having keys corresponding to the different magnets and signals.

140. A party-line telephone system comprising signal-transmitting apparatus adapted for sending vibratory currents of different character, and a plurality of non-tuned reactive signal-receiving means suitably connected with said signal-transmitting apparatus, said signal-receiving means including a plurality of signal-magnets, and means whereby each magnet when sufficiently energized produces a signal, each signal-magnet being responsive to its allotted character of current and no other, and the said transmitting and receiving apparatus being adapted, by reason of the different degrees of impedance offered by the receiving apparatus to vibratory currents of different character, to conjointly increase and decrease the relative flow of current in the different magnets, whereby the different currents may be used to selectively produce the different signals, said signal-transmitting apparatus including a switching device having keys corresponding to the different magnets and signals; and a telephone set allotted to each signal-receiving means and designated by the signal given thereby, together with a talking-circuit for each telephone set, the talking-circuits of the different telephone sets being in part coincident with each other, and each said talking-circuit being in part coincident with a signaling-circuit; and means for supplying the current necessary for operating said telephone sets, said means being independent of and distinct from the means employed for furnishing the current necessary for operating the different signal-receiving means.

141. An electric signaling system comprising signal-transmitting apparatus adapted for sending vibratory currents of different reactive character, non-tuned reactive signal-receiving apparatus suitably connected with said signal-transmitting apparatus, said signal-receiving apparatus including a plurality of signal-magnets, and means whereby each magnet when sufficiently energized produces a

signal, each signal-magnet being responsive to its allotted character of current and no other, the transmitting and receiving apparatus thus provided being adapted, by reason of the different degrees of impedance offered by the receiving apparatus to vibratory currents of different character, to conjointly increase and decrease the relative flow of current in the different magnets, as the character of the current changes, whereby the different currents may be used to selectively produce the different signals, said signal-transmitting apparatus including a switching device having keys corresponding to the different magnets and signals, the different signal-receiving means being each adapted and designed independently of any signaling action of the other to perform its intended function of giving a signal to attract attention.

142. A party-line telephone system comprising signal-transmitting apparatus adapted for sending vibratory currents of different reactive character, a plurality of non-tuned reactive signal-receiving means suitably connected with said signal-transmitting apparatus, said signal-receiving means including a plurality of signal-magnets, and means whereby each magnet when sufficiently energized produces a signal, each signal-magnet being responsive to its allotted character of current and no other, the transmitting and receiving apparatus thus provided being adapted, by reason of the different degrees of impedance offered by the receiving apparatus to vibratory currents of different character, to conjointly increase and decrease the relative flow of current in the different magnets, as the character of the current changes, whereby the different currents may be used to selectively produce the different signals, said signal-transmitting apparatus including a switching device having keys corresponding to the different magnets and signals; and a telephone set allotted to each signal-receiving means and designated by the signal given thereby, together with a talking-circuit for each telephone set, the talking-circuits of the different telephone sets being in part coincident with a signaling-circuit; and means for supplying the current necessary for operating said telephone sets, said means being independent of and distinct from the means employed for furnishing the current necessary for operating the different signal-receiving means.

In witness whereof I hereunto subscribe my name this 3rd day of February, A. D. 1900.

OSCAR M. LEICH.
